COMBINATION GRINDING AND POLISHING MACHINE

John T. Armbruster, Niagara Falls, N.Y., assignor to
American Optical Company, Southbridge, Mass.

Filed Feb. 23, 1962, Ser. No. 68,951

Term of patent 14 years

(Cl. D37—1)

FIG. 1 is a top-front-end perspective view of the combination grinding and polishing machine showing my new design;

FIG. 2 is a top plan view thereof;

FIG. 3 is a bottom plan view thereof, the grinding and polishing wheels being omitted for convenience of illustration; and

FIG. 4 is an enlarged fragmentary view illustrating the pattern on the left end of the body of the machine as shown in FIG. 1.

The rear and end not shown are substantially the same

in appearance as the front and end, respectively, as shown in FIG. 1.

The dominant features of my design reside in the portions shown in full lines.

I claim:

The ornamental design for a combination grinding and polishing machine, substantially as shown and described.
